Primary Examiner—Sandra L. Morris*Assistant Examiner*—Richelle Shelton*Attorney, Agent, or Firm*—Howrey & Simon; Michael J. Bell[57] **CLAIM**

The ornamental design for a peripheral groove in a front surface of a basketball backboard, as shown and described.

DESCRIPTION

FIG. 1 is a front elevational view of a portion of a front surface of a basketball backboard showing one embodiment of our new design;

FIG. 2 is an enlarged cross sectional view thereof taken along lines 2—2 in FIG. 1;

FIG. 3 is a front elevational view of a peripheral groove in a front surface of a basketball backboard showing a second embodiment of our new design;

FIG. 4 is an enlarged cross sectional view thereof taken along lines 4—4 in FIG. 3; and,

FIG. 5 is a front elevational view of a peripheral groove in a front surface of a basketball backboard showing a third embodiment of our new design.

The broken lines which define the metes and bounds of the claimed design form no part thereof.
